WRENCH FOR CAMERA LENS, FILTERS AND THREAD ADAPTORS

Jody L. Numbers, 2202 S. Priest, Suite 102,
Tempe, Ariz. 85282

Filed Apr. 29, 1974, Ser. No. 465,372

Term of patent 14 years

Int. Cl. D8—05

U.S. CL. D8—17

FIG. 1

FIG. 2

FIG. 3

FIG. 4

FIG. 5

FIG. 6

FIG. 1 is a front view of the wrench for camera lens, filters and thread adaptors disclosed;

FIG. 2 is a right end view of the wrench shown in FIG. 1;

FIG. 3 is a cross-sectional view of the wrench shown in FIG. 1 taken along the line 3—3;

FIG. 4 is a perspective view of one side, top and end of the wrench shown in FIG. 1;

FIG. 5 is a perspective view of the other side, bottom and other end of the wrench shown in FIG. 4; and

FIG. 6 is a top view of the structure shown in FIG. 1 taken along the line 6—6.

I claim:

The ornamental design for a wrench for camera lens, filters and thread adaptors, as shown and described.
